UNITED STATES PATENT OFFICE

FREDERICK A. ANTON, OF TOPEKA, KANSAS

AWNING ROLLER

Application filed September 24, 1930. Serial No. 484,022.

This invention relates to awning rollers and has for its objective the provision of ends for such rollers such as shall insure a proper winding thereon of the awning fabric without subjecting the same to stretching strains which not only shorten the life of the fabric but permit it, when in spread or operative position, to sag at opposite sides of the central portion near its side margins, and therefore present an unsightly or unattractive appearance.

As well known, awning fabrics are provided with side hems and when used in conjunction with the conventional awning rollers, invariably stretch and sag as adverted to above, after a comparatively short period of service, and this is especially noticeable with large awnings, because of their weight they offer such resistance that they wind tightly on the rollers. The conventional roller, as well known, being of uniform diameter from end to end, causes the hemmed ends of the fabric as the awning is wound up, to increase in diameter more rapidly than the body of the fabric, and in so doing the fabric is subjected to a laterally applied strain which stretches the body of the fabric near the side or hemmed margins, and also tends to cause the fabric to creep or shift laterally and thus present an uneven and more or less unsightly appearance at the ends when fully wound upon its roller.

I have found by experimentation that, through the use of a roller of reduced end diameter, an awning fabric, with hemmed side margins, can be wound smoothly without creepage and when rolled up will be of substantially uniform diameter from end to end so that its appearance is attractive. This construction also avoids all undue lateral straining or stretching of the fabric so that when the awning is open or spread, it is taut for its entire area and avoids the very unsightly sagging mentioned, near its side margins.

My primary object, therefore, is the provision of a roller, of either the wood or metal type, upon which a side hemmed fabric can be wound smoothly and of substantially uniform diameter without creepage or appreciable lateral stretching near its side margins.

The invention broadly consists of the provision of a roller which has end extremities of cylindrical form and less diameter than the body of the roller, and which is symmetrically tapered from the body portion to such reduced end portions, the length of the tapered portions being sufficient to avoid any abrupt deflection or bending of the fabric as it is being wound upon or unwound from the roller.

Another object is to provide a roller of the characteristic type mentioned, comprising a body portion of uniform diameter and gudgeon ends secured to the body portion and constituting the reduced and tapered portions upon which the hemmed side margins of the fabric wind and unwind.

With the objects mentioned in view, the invention consists in certain novel and useful features of construction and organization of parts as hereinafter described and claimed; and in order that it may be fully understood, reference is to be had to the accompanying drawings, in which:

Figure 1 is a fragmentary view, partly in elevation and partly in diametric section of a roller embodying the invention, the fabric wound thereon being also disclosed.

Figure 2 is an end view of the same with the fabric omitted.

Figure 3 is a fragmentary perspective view of a wood roller embodying the invention, the roller proper being partly withdrawn from the gudgeon.

In the said drawings, where like reference characters identify corresponding parts in all of the figures, 1 is the shaft which may extend through the roller 2 or may consist of alined extensions or trunnions secured to the reduced ends of the roller, as hereinafter more particularly referred to.

As shown gudgeons form the ends of the roller 2 which is illustrated as of the metal type, one gudgeon only being shown, and each comprises essentially a head 4 of the same diameter as the roller at one end, and of lesser diameter at the other end, and a star-shaped stem 5 of size to fit snugly in the roller. If no shaft 1 is employed the gudgeon will be reduced at its outer end to

form a trunnion 6 (see Figure 3), the stem and trunnion being coaxially disposed with respect to the head. The head tapers symmetrically and gradually from its inner or 5 large end to within an inch or three-quarters of an inch of its opposite end, and thus provides a small cylindrical end portion 7, of uniform diameter, and of length slightly exceeding the width of the related hem of the 10 awning fabric.

The stem of each gudgeon is fitted snugly into the respective end of the roller until the 15 enlarged end of the head abuts against the opposing extremity of the roller, and a pin 8 extends through the roller and stem, to make the connection secure. If the shaft 1 is employed, as shown in Figures 1 and 2, the 20 gudgeon is secured upon it by the same pin. If the shaft is dispensed with, as hereinbefore suggested, the head will be provided with the trunnion 6, projecting axially from its small end. In the one case, the extremities 25 of the shaft, and in the other, the trunnions of the gudgeons will be journaled in suitable bearings, not shown, so that the roller shall lie in a horizontal plane.

In Figure 3, the construction of the gudgeon is identical with that described except that the stem 5a is flat in shape to fit in a 30 diametric slot or space 9 in a wood roller. Preferably, the wood roller is composed of two semi-cylindrical sections 10 having their flat faces at their ends, fitting against opposite sides of the stem and secured to the latter 35 by the pin 8.

The width of the awning fabric 11, corresponds to the length of the roller, and the width of the hems 12 correspond approximately to that of the reduced cylindrical portions 40 of the roller, as indicated in Figure 1, and it will be noted, as approximately shown in said figures, that although the hem doubles the thickness of the fabric, the reduction of the end portions of the roller compensates therefor, and as a consequence the 45 external diameter of the fabric when wound up is approximately uniform, and hence is not under any appreciable lateral stretching strain so that when spread or open it presents no appreciable or noticeable sagging at or 50 near its side margins.

From the above description it will be apparent that while I have described and 55 claimed a construction embodying all of the features set forth as desirable and of simple and inexpensive construction, it is to be understood that I reserve the right to make all changes properly falling within the spirit of the invention and without the ambit of the 60 prior art.

I claim:—

1. An awning roller having its end extremities of reduced diameter and having a reverse curve merging into reduced ends from 65 the body of the roller.

2. An awning roller comprising a central shaft, a tubular roller carried by said shaft, a gudgeon mounted on said shaft and interlocked with the roller and having a shoulder portion of the same diameter as the roller 70 and in abutment therewith, the other end of said gudgeon being of less diameter than the shoulder portion and of greater diameter than the shaft.

3. An awning roller comprising a central 75 shaft, a tubular roller carried by said shaft, a gudgeon mounted on said shaft and interlocked with said roller and having a shoulder portion of the same diameter as the tube and in abutment therewith, the other end of said 80 gudgeon being of less diameter than the shoulder portion, and an intermediate curved portion merging at its opposite ends into the reduced end and shoulder portions respectively. 85

4. The combination with an awning roller, of a gudgeon axially alined and interlocked therewith, said gudgeon having a shoulder portion of equal diameter to the roller, an intermediate reduced portion, and a trunnion extremity. 90

5. The combination of a gudgeon consisting of a head tapering outwardly and terminating at its outer end in a cylindrical portion and forward thereof in a trunnion of 95 smaller diameter than the cylindrical portion; the head having a flat diametric extension at its inner end, a roller composed of semi-cylindrical sections fitting at their flat faces upon the said extension, and means securing the roller sections to said extensions. 100

In testimony whereof I affix my signature.
